UNITED STATES PATENT OFFICE.

WILLIAM A. PHILLIPS, OF THE UNITED STATES ARMY.

ELECTRICAL DANGER-SIGNALING SYSTEM.

SPECIFICATION forming part of Letters Patent No. 529,949, dated November 27, 1894.

Application filed May 29, 1893. Serial No. 475,914. (No model.)

To all whom it may concern:

Be it known that I, WILLIAM A. PHILLIPS, second lieutenant Twenty-third Infantry, United States Army, a citizen of the United States, residing at Fort Keogh, in the county of Custer and State of Montana, have invented certain new and useful Improvements in Electrical Danger-Signaling Systems; and I do hereby declare the following to be a full, clear, and exact description of the invention, such as will enable others skilled in the art to which it appertains to make and use the same.

My invention relates to improvements in electric danger signals for block railway systems, whereby liability of accidents occurring from collisions and open switches is obviated.

The object of the invention is to provide improved means by which alarms are sounded from a train on one block to a train or trains on either or both the adjacent blocks, the alarms being sounded on all the trains, whether they are standing still, or approaching toward or receding from each other.

It is also an object to provide improved means for signaling to an approaching train that a switch is open; also to provide an improved switch board for use on the trains and at a station, whereby signals may be transmitted from a train or trains to the station, and by which the operator at the station can ascertain in which direction a train is approaching or whether a switch is open, and also by which the operator on a train can tell whether an alarm sounded on his train comes from a train on an adjacent block or from an open switch.

There are other objects and advantages which will be apparent to those skilled in the art to which the invention pertains.

The invention consists essentially in three parallel conductors for each block, arranged between the rails thereof, the center conductor of each block, which I term the "battery" conductor being connected with one of the conductors on each side which I term the "bell" conductors, of the two adjacent blocks. Contacting with these battery or center conductors is a brush on a locomotive which is electrically connected with an electric battery in the cab; which battery is also connected with a ground conductor. Contacting with

the other or bell conductors are two brushes on the locomotive which are electrically connected with an electric bell, also connected with the ground or return conductor. Interposed in the circuit between the bell and battery is a switch board by means of which the engineer can ascertain whether the alarms sounded by the bell are produced by a train on an adjacent block, by an open switch, or come from the station, the station being supplied with a similar board in electric-communication with a battery and bell and with the said battery and bell conductors. There is also an improved switch bar which when a switch is open will establish a circuit between the same and the station and an approaching train. The said improvements will be hereinafter fully set forth in detail and specifically pointed out in the claims.

In the accompanying drawings,—Figure 1 shows in diagram and elevation the manner of establishing a circuit between two trains and with a train and station according to my invention. Fig. 2 is a diagrammatic view of a signaling system according to my invention. Fig. 3 is a similar view showing the invention applied to a switch. Fig. 4 is an elevation showing my improved switch board. Fig. 5 is a diagrammatic view of the switch board showing the binding posts located and arranged somewhat differently. Fig. 6 is a diagram showing my improved signal as applied to a railroad crossing. Fig. 7 is a side elevation of the switch board. Figs. 8 and 9 are views showing how the brushes are supported. Figs. 10 and 11 are detail plan and side views, respectively, of one of the brushes, on an enlarged scale.

In the said drawings, referring now more especially to Figs. 1 and 2, I have shown three block sections of a railway, numbered respectively, "Block No. 1," "Block No. 2," and "Block No. 3." In each of these sections centrally between the rails, is a battery conductor z , z' , z^2 , and at each side thereof are bell conductors x , x' , x^2 , and y , y' , y^2 ; the conductor x , being electrically connected to z' by connection k' ; conductor z by connection h' with y' ; conductor x' by k^2 with z^2 ; z' by h^2 with y^2 , and so on throughout all the blocks of the road. Contacting with these conductors are brushes which establish circuit be-

tween the same and the train. These conductors, in practice, will be in the form of chains or brushes connected with the battery and bell in locomotive cab, as will be herein-
 5 after more fully described, but in Figs. 1 and 2, they are simply shown as wires. The wires c , which contact with the central track conductors lead to binding post A on the locomotive and from thence pass to the battery
 10 P, a wire f connecting the battery with ground conductor t . The conductors c' and c^2 , which contact respectively with the bell conductors, connect with an ordinary electric bell B in the cab which in turn is connected with ground
 15 wire t , by return wire g .

The operation of the parts so far described is as follows: Supposing that a train is on block No. 2, and that another train enters block No. 1, as soon as the conductor c of
 20 this last mentioned train contacts with the conductor z then a circuit will be established from the battery of this train through conductors z , h' , y' , c^2 and bell B of train on block No. 2, sounding an alarm thereon, and
 25 from thence through g and ground conductor t , back to battery. In like manner an alarm will be sounded from train on block No. 2, to train on block 1, the circuit being from battery of the train on block 2, through c , z' , k' ,
 30 x , c' , to bell on train on block No. 1, g and t , back to battery. It will thus be seen that battery on one train sounds the alarm or rings the bell of the other train. In a similar manner alarms will be sounded by a train on
 35 block No. 3, and the alarms will be sounded whether all the trains are moving or if one be stationary, as will be readily understood by those skilled in the art to which the invention pertains.

40 I will now describe the means for sounding an alarm when a switch is open.

Referring to Fig. 3, in which the battery and bell conductors are placed outside the rail instead of between them as before de-
 45 scribed, the letters S, S, designate the main track rails, and t' , t' , the switch rails. Connected with said rails S, S, is a switch bar 23^x, provided with the usual operating lever. The free end of this switch bar is provided with
 50 an extension forming a conductor t^2 , provided with conducting arms x^3 , y^3 , z^3 , which when the switch is open will contact respectively with the said battery and bell conductors. Sup-
 55 posing now that the switch shown in Fig. 3, was connected with block No. 2, and a train was approaching from block No. 1, then the operation would be as follows: Circuit would be established through battery P, conductors c , z , h' , y' , z^3 , t^2 , y^3 , z' , k' , x , c' , bell B, g , t , back
 60 to battery, sounding an alarm on said bell. In this case the bell is rung by the battery on its train, instead of by a battery on another train as first above mentioned. If the train were approaching in the opposite direc-
 65 tion or from block No. 3, then the circuit would be from battery on the train or cab through its conductor c , z^2 , k^2 , x' , x^3 , t^2 , y^3 , z' ,

h^2 , y^2 , c^2 to bell and thence to ground. When the switch is closed conductors x^3 , y^3 , z^3 , are thrown out of contact with the track conductors so that no alarm is sounded.

70 For the purpose of signaling to and from a train or trains to and from a station, and also for the purpose of ascertaining whether an alarm sounded is caused by a train or by an open switch, I construct a switch according to Figs. 4 and 5; the switch board shown interposed in circuit between the battery and bell and the cab or train and with a battery and bell in a station. The batteries, bells, 75 switch board and connections of the trains and station are identical in construction and operation.

The switch board shown in Fig. 5, which I will describe with reference to a station, differs somewhat in minor details, such as the location of the binding posts, but in principle and mode of operation they are alike.

Referring now to Fig. 5, the station is shown as being located in block No. 2, and provided with a battery P, and bell B. This switch board comprises a circular plate or disk H, of non conducting material having arranged in pairs in a concentric circle, a number of conducting plates 1—2, 3—4, 5—6, 95 7—8, 9—10, 11—12, 13—14, and 18—19, and also three similar plates 15—16—17. The letters V, W, X, Y, and Z, designate binding posts. Pivoted to this disk at the center thereof is a segment or arm H' of non-conducting material, provided near its edge at the center and near each end with conductors a, b, c, which are adapted to connect any of said plates 1—2, &c., together when placed over the same. Connected with the 100 battery conductor z' , is a conductor v, leading to binding post Y, from which extend conductors leading, respectively, to plates 6, 8, and 16. Connected with conductors y' is a conductor u, leading to binding post Z from 105 which extend conductors u' , u^2 , u^3 , leading respectively to plates 4, 11, and 15. Connected with conductor x' is a conductor w, leading to binding post X from which extend conductors w' , w^2 , w^3 and w^4 leading respectively to plates 2, 10, 13 and 17. Leading from binding post W is a conductor M connected with the bell, and conductors w^6 , w^7 , w^8 , w^9 , w^{10} , leading respectively to plates 1, 3, 9, 12, 115 14 and 18. Connected with binding post V, 110 is a conductor N connected with battery P, and conductors v^4 , v^5 , v^6 , leading respectively to plates 5 and 7 and 19.

The operation of the switch board is as follows:—When in normal position the segment arm of key is in the position shown in Fig. 5, with the blocks a, b and c connecting respectively the plates 1—2, 3—4 and 5—6. If now a train approaches the station from the south or No. 1 block, an alarm will be sounded 125 on the train, the circuit being from battery in station conductors N, V, v^4 , 5, c, 6, v' , Y, v , z' , k' , x , to bell in car to ground. At the same time the bell in station will be sounded,

the circuit being from battery on train to z , h' , y' , u , Z , u' , 4 , b , 3 , w^7 , W , M , to bell and to ground. If the train approaches on the north or No. 3 block, the circuits will be from battery in station to N , V , v^4 , 5 , c , 6 , v' , v , h^2 , y^2 to bell on train and ground, and from battery on train to z^2 , x' , w , X , w' , 2 , a , 1 , u^6 , W , M , to bell in station and ground.

To ascertain from which direction the train is approaching, the operator swings the segment arm to the right breaking the connection with 1 and 2, thus cutting out the north or No. 3 block. If the bell now stops ringing, the operator will know that the alarm was sounded from a train on said block; but if on the contrary, the bell continues to ring he will know that it is sounded from a train on block No. 1, or south block, or from an open switch. To ascertain whether the alarm is caused by a train on block No. 1, or an open switch, the operator turns the segment arm or key still farther and cuts out 3 and 4, or No. 1 block. If the bell now stops ringing the alarm was caused by a train on block No. 1, but if it still continues to ring it was caused by an open switch. The circuit will now be from battery in station to N , V , v^4 , 5 , c , 6 , v' , Y , v , z' , y^3 , t^2 , x' , w , X , w^2 , 10 , c , 9 , W , M , to bell in station to ground. To cut out the station battery so as to allow the station bell to be sounded from the train without an alarm being sounded in the train, the segment arm is moved so that the blocks a , b , c , will connect respectively plates 9—10, 11—12, and 35 13—14, cutting out entirely the station battery. Signals may now be sent from a train on block No. 3, the circuit being from battery on train to z^2 , k^2 , w , X , w^3 , 13 , c , 14 , w^{10} , W , M , to bell and ground. To signal from No. 1 block the circuit would be from battery to z , h' , y' , u , Z , u^2 , 11 , b , 12 , W , M , to bell and ground. By placing one of the blocks over 15, 16, 17, it acts as a danger key sending alarms to trains approaching in either direction, the circuit being from battery in train on block No. 1, to z , h' , y' , u , Z , u^3 , 15 , b , 16 , v^3 , Y , v , z' , k' , x to bell on train to ground. To signal a train on block No. 3, the circuit will be from battery on train to z^2 , k^2 , x' , w , X , w^4 , 17 , 16 , Y , v , z' , h^2 , y^2 , to bell on train and ground.

When the key or segment arm is turned to point marked "Cut out" on the switch board the station and trains are entirely cut out.

55 The plates 18 and 19 are used for testing whether the mechanism is in proper working order. By placing one of the blocks of the key, say b , over the same, so as to electrically connect them together, all of the conductors are cut out except the battery and bell. The circuit in this case will be from battery to N , N , v^6 , 19 , b , 18 , v^{12} , W , M , to bell and ground.

65 While I have described the switch board as being used in connection with a station, it is obvious that it can be used on a train and operated in a similar manner to signal to a

station or to another train, as will be readily understood by those skilled in the art to which the invention pertains. In Fig. 6, I have 70 shown my improvements applied to a crossing of two railroads, both when only one of the roads is provided with the system and when both the roads are provided with it.

If only one of the roads is provided with the system then on that road, near its junction with the other road, the track conductors are carried to one side, and three short conductors 35, 35, and 36, electrically connected together are inserted between the 80 rails, at the bend formed by the turning aside of said main conductors. This will be clearly seen in Fig. 6. As the train approaches the crossing the battery conductor thereof will contact with the central conductor and the 85 bell conductors with the side conductors, thus completing the circuit, between the battery and bell and ringing an alarm notifying the engineer that the train is approaching a crossing. The circuit will be from battery 90 and its conductor and brush, to central conductor 36, then by end connections 37, to side conductors 35, then to bell conductors of the train to bell and thence to ground. As soon as the train passes the short conductors so 95 that the brushes will be out of contact therewith, the bell will stop ringing. When the other track or road is provided with the improvements the construction and operation will be the same in every respect. These 100 short conductors may also be placed at the approaches of bridges and other places, and any number of them can be inserted, and by varying their length making some of them long and some short, the bells may be made 105 to sound a long or short alarm as the case may be. By properly arranging these short conductors different combinations of letters may be sounded after the manner of the Morse alphabet. For example, the letter A may be 110 signaled by making a short and long inserted block, which shall give a short and a long ring to the bell of the train passing over it. The letter B may be sounded by a reverse arrangement, the bell given a long and then a 115 short ring. These different signals will represent different places. For instance, letter A may indicate the approach to a bridge and letter B a road crossing. Permanent signals where a stop is always necessary are made 120 by inserting these short conductors or blocks. When intersecting roads occur both of which roads are provided with my improvements the blocks of the main tracks of each road, are located away from the crossing and within 125 in stopping distance of the crossing, or the conductors one each side of the crossing are carried over on poles.

In order to prevent there being a possibility of two trains entering upon a block at exactly 130 the same instant the conductors at the end of the block overlap or pass by each other a short distance.

When a short block is inserted the extra

connected conductors occupy the spaces between the regular conductors as shown in the drawings. At a road crossing the conductors are discontinued for a space and insulated 5 conductors run beside the track.

I will now proceed to describe in detail the construction of the track conductors and train conductors.

Referring to Figs. 8 and 9, the numerals 1^a, 10 designate brackets depending from the under side of a car to the lower ends of which is pivoted a plate 3^a carrying at each end a downwardly depending plate 8^a. These plates are connected by an adjustable rod 9^a pivoted at 15 each end to said plates and connected at their inner ends by a swivel. By this construction the plates may swing back and forth, so as to allow any obstruction on the track to raise the entire brush 10^a from the conductors and permit 20 the obstruction to pass. The brush consists of a flat chain secured at each end to said plates 8^a and provided with downwardly depending pins 31, which form contact points with the track conductors. There are three 25 of these brushes employed on each engine or cars one for each of the track conductors. These chains or brushes consist of a number of links 32, connected together by pins 33, and 30 34 designates pins from which the contact pins 35 or fingers 31 are suspended. The numeral 11^a designates binding posts one to each brush, with which the conductors leading to the said brushes are connected. The conductor leading to the central binding post is connected 35 with the battery of the locomotive, while the others are connected with the bells.

The track conductors are secured to the rails as follows: The numeral 13^a designates a bracket passing under the rail and secured 40 by means of a screw 14^a. 30 is a block inserted between the bracket and rail. This bracket is formed with an extension provided with an insulating plate 25, upon which the track conductors are supported with insulating blocks 45 21, 22, 23, 24, interposed between the brackets and conductors. The numeral 19^a designates a binding screw and 20 a plate working on the reduced end of plate 25, by which the insulating plates and conductors are held in place.

Having thus fully described my invention, 50 what I claim is—

1. In an electrical signaling device for block system railways, the combination with the three parallel track conductors for each block, 55 the central one of each block being electrically connected with one of the conductors of each adjacent block at opposite sides of said central conductor, of the conductors carried by a car, one of which is connected with a battery on 60 the car and said central track conductor and the others connected with a bell in said car and with said side track conductors, substantially as and for the purpose specified.

2. In an electrical signaling device for block 65 system railways, the combination with the three parallel track conductors for each block, the central one of each block being electrically

connected with one of the conductors of each adjacent block at opposite sides of said central conductor, of the conductors carried by a car, 70 one of which is connected with a battery on the car and said central track conductor and the others connected with a bell in said car and with side track conductors, and a switch board interposed between and in circuit with 75 said battery and bell, substantially as described.

3. In an electrical signaling device for block system railways, the combination with the three parallel track conductors for each block, 80 the central one of each block being electrically connected with one of the conductors of each adjacent block at opposite sides of said central conductor, of the conductors carried by a car, one of which is connected with a battery on 85 the car and said central track conductor and the others connected with a bell in said car and with said side track conductors, the switch board interposed between and in circuit with said battery and bell, the conductors connected with said track conductors and leading to a station and the battery and bell connected with said station conductors, substantially as described.

4. In an electrical signaling device for block 90 system railways, the combination with the three parallel track conductors for each block, the central one of each block being electrically connected with one of the conductors of each adjacent block at opposite sides of said 95 central conductor, of the conductors carried by a car, one of which is connected with a battery on the car and said central track conductor and the others connected with a bell in said car and with said side track conductors, the switch board interposed between and in circuit with 100 said battery and bell, the conductors connected with said track conductors and leading to a station, the battery and bell connected with said station conductors and a switch board interposed between 105 and in circuit with said station battery and bell, substantially as described.

5. The combination with the electrical track 110 conductors, of the electrical brushes carried by a car and comprising a series of pins strung upon pivoted links connected with pendent side plates, the rods pivoted to said side plates and their inner ends connected together by a swivel or turn buckle, to permit the brush to readily free itself from obstruction, substantially as described.

6. In an electrical signaling device for block 115 system railways, the combination with the three parallel track conductors for each block, 120 the central one of each block being electrically connected with one of the conductors of each adjacent block at opposite sides of the central conductor, the brushes carried by a car, one of which is connected with a battery 125 on the car and with said central track conductor and the others connected with a bell in said car and with said side track conductors, of the three short conductors, electrically 130

connected to each other, and interposed at certain points where the said track conductors are deflected for such purpose, and so arranged that when the brushes of a car pass over the same, a circuit will be established, substantially as described.

7. In an electrical signaling device for block system railways, the combination with the three parallel track conductors for each block, the central one of each block being electrically connected with one of the conductors of each adjacent block at opposite sides of the central conductor, the brushes carried by a car, one of which is connected with a battery on the car and with said central track conductor, and the others connected with a

bell in said car and with said side track conductors, of the switch, the sliding bar connected therewith and operated thereby, and provided with three perpendicular electrically connected prongs which contact with said track conductors and thus electrically connecting them when the switch is opened to connect the main line rails to the side track rails, substantially as described. 25

In testimony whereof I affix my signature in presence of two witnesses.

WILLIAM A. PHILLIPS.

Witnesses:
